UNITED STATES PATENT OFFICE.

R. EDWARD BALL, OF NEW YORK, N. Y.

DYNAMO-ELECTRIC MACHINE.

SPECIFICATION forming part of Letters Patent No. 280,439, dated July 3, 1883.

Application filed October 20, 1882. (No model.)

To all whom it may concern:

Be it known that I, R. EDWARD BALL, a citizen of the United States, residing at New York, in the county of New York and State of New York, have invented certain new and useful Improvements in Dynamo-Electric Machines, of which the following is a specification, reference being had therein to the accompanying drawings, wherein—

10 Figure 1 is a perspective of my improved dynamo-electric machine; and Fig. 2 is a theoretical elevation, illustrating the relative position of armatures, field-magnets, commutators, brushes, and electrical connections or circuits therefor.

15 My invention has relation to dynamo-electric machines, and has for its object to provide a dynamo of great capacity, electro-motive force, and an increased efficiency in practical effect.

20 To this end my invention accordingly consists of the novel construction, combination, and arrangement of parts, having reference to the following points: first, to the provision 25 of two sources for the generation of electric energy—viz., the mutual or reciprocal inductive reaction of the armatures on each other and the inductive action of the field-magnets on the armatures, whereby the capacity of the 30 machine is greatly increased; second, to the provision of armatures whose points of polarity are brought closer to the pole-pieces of the field-magnets than has heretofore been the case, whereby an increase of electro-motive 35 force is obtained; and, third, to the provision of means for reducing the resistance of the armatures and diminishing the heating of the same, whereby an increased efficiency in practical effect is produced.

40 Referring to the accompanying drawings, A A' represent two armatures mounted on shafts a a', respectively, having bearings in a suitable frame, as indicated. The armatures A A' are provided with their respective commutators, B B', and they consist of an endless coil or series of coils connected together to form a ring, in a manner substantially similar to the Paccinotti armature. They are placed parallel to and revolve contiguous to one another, 45 being but slightly separated, so that they will not impinge or contact as they rotate.

C C' represent field-magnets arranged as illustrated, or they may otherwise be suitably disposed. c c are the pole-pieces thereof, arranged to form common pole-pieces for both 55 armatures B B'; but I prefer to curve said pole-pieces around the armatures, as illustrated, as such arrangement brings the field of magnetic action more nearly between the contiguous portions of the armatures, while their opposite or outer sides are beyond or free from such influence. Each commutator is provided, respectively, with the usual or other suitable brushes, E E', and F represents a brush common to both commutators. As the 60 brushes locate the polarity-points in the armatures, each one of the latter therefore has three points of polarity, as indicated in Fig. 2. In one armature two of the points are of north polarity, and the remaining point there- 70 of is of south polarity, while in the other armature two points are of south polarity and the remaining point of north polarity. The electric connections or circuits between such parts are substantially as follows: 1 1 represent the 75 external circuit from binding-post 2. A wire leads to magnets C, and from the latter proceeds a wire, 3, which splits into two branches, which connect with the brushes E E' of commutator B. The circuit is then into and 80 out of armature A, and thence by way of brush F to commutator B', thence into and out of armature A' to brushes E' E' of commutator B', thence by way of branches of split wire 4 to magnets C', and thence by wire 5 to binding- 85 post 6, to external circuit, the place of starting. It will thus be seen that a split circuit or current is provided for between the usual brushes of the commutators and the field-magnets, and such current will equally divide itself, for the 90 reason that the resistances between said brushes and the brush common to both armatures are equal. By such arrangement of brushes and circuits the points of polarity of the armatures are brought close up to the pole-pieces, as indicated in Fig. 2, thereby increasing the magnetic intensity of the currents generated thereby and leaving the exterior sides, a a', of the armatures free of inductive action or current influences; hence as the armatures pass 95 through that part of their revolution from z z their coils will be cooling, and the heating of 100

the armatures for this reason is also diminished. Again, the use of said split current to the brushes permits of the diminishing of the length of the pole-pieces of the field-magnets, and thereby increasing their magnetic intensity and correspondingly affecting the electro-motive force of the machine, for it can be shown by experiment that the capacity of an armature is not diminished, but in fact is slightly increased, by reducing the length of the arc of its field-piece and the corresponding coils in electrical action to a point amounting to about one-fourth of the circumference of the armature, the reason wherefor would appear to be that although the amount of wire in electrical action may be diminished, yet at the same time the magnetic intensity of the field-pieces is increased by concentration, and as a result about the same capacity with a less resistance of armature is obtained. The heating of the armatures being diminished and the resistance therein decreased and their capacity remaining the same, it follows that there is an increased efficiency in practical effect of the current generated, because very little of such current is consumed in the internal circuit. The polarity-points of the armatures being closer to the pole-pieces of the field, the magnetic intensity of the currents generated is increased, and correspondingly the electro-motive force of the machine is enhanced. Again, as the armatures A, A' pass each other at the point α the magnetic polarity-point of each armature induces a current in the opposite armature; hence the reciprocal reaction of the armatures provides a source for the production of electric energy in addition to that effected by the action of the field-magnets thereon. Consequently I have two sources for the generation of such energy, and the capacity of the machine is therefore greatly increased. Such increase is obtained without adding to the internal resistance, while on the other hand, although the resistance in the armatures is decreased, yet there is obtained an increase in the efficiency of the dynamo in practical effect and a diminution in the heating of the armatures.

I have shown my invention provided with two armatures; but, if desired, three or more may be used. So, too, instead of employing a brush, F, common to both armatures, it may be divided into two brushes—one for each armature—said brushes being electrically connected together or in circuit with each other.

What I claim as my invention is—

1. In a dynamo-electric machine, the combination of field-magnets having pole-pieces common to two armatures, located and revolving upon separate shafts, said armatures being in common circuit with the field-magnets, mutually inducing currents in each other of the same direction as that of those induced in them by the field-magnets, substantially as shown and described.

2. In combination with two armatures having separate shafts, commutators, and brushes, and electro-magnets in common circuit with said armatures, and whose pole-pieces are common to the latter, which mutually induce each other and are induced by said field-magnets, substantially as set forth and described.

3. The combination, with two armatures having separate shafts, commutators, and brushes, of a brush common to two of said commutators and field-magnets having pole-pieces common to both said armatures, substantially as shown and described.

4. A dynamo-electric machine having two armatures mounted on separate shafts, with their respective commutators and brushes, brushes or connections between the commutators, and a split circuit from the field-magnets to brushes of like polarity, substantially as shown and described.

5. A dynamo-electric machine having a series of armatures, each of which is composed of an iron ring or core and endless coils or sections of insulated wire, and which mutually react upon one another, in combination with field-magnets in common circuit with said armatures, substantially as shown and described.

6. A dynamo-electric machine composed of two armatures composed of iron rings or cores and an endless coil of sections or bobbins, and a field of force having a centrally-located field of magnetic action, the opposite or outer sides of the armatures being free from such action, so as to provide for the successive cooling of the coils of the armatures, substantially as shown and described.

7. In a dynamo-electric machine, a split or divided circuit connected to commutator-brushes of like polarity, whereby the polarity-points of the armatures are brought close up to the pole-pieces of the field-magnet, substantially as shown and described.

8. The combination, in a dynamo-electric machine, of armatures, field-magnets, a common circuit therefor, pole-pieces for said magnets, commutators, and brushes, arranged substantially as shown and described, whereby the armatures mutually induce each other and are induced by the field-magnets for producing electrical energy in like direction, as set forth.

9. The combination, with two armatures having separate shafts, commutators, and brushes, of a brush common to both said commutators and field-magnets having pole-pieces common to both said armatures, substantially as shown and described.

In testimony whereof I affix my signature in presence of two witnesses.
